UNITED STATES PATENT OFFICE

150,955

DESIGN FOR A KNIFE SHARPENER

Earl E. Jacobs, Dayton, Ohio

Application August 15, 1946, Serial No. 132,554

Term of patent 14 years

(Cl. D37—1)

To all whom it may concern:

Be it known that I, Earl E. Jacobs, a citizen of the United States, residing at Dayton, Montgomery County, Ohio, have invented a new, original, and ornamental Design for a Knife Sharpener, of which the following is a specification, reference being had to the accompanying drawing, forming a part thereof, in which

Fig. 1 is a perspective view of a knife sharpener, embodying my new design; and

Fig. 2 is an enlarged fragmentary view, showing the lines of demarcation between the roughened and plain portions of the knife sharpener shown in Fig. 1.

I claim:

The ornamental design for a knife sharpener, substantially as shown and described.

EARL E. JACOBS.
